UNITED STATES PATENT OFFICE

WILLIAM E. COOPER, OF BROOKLYN, NEW YORK, ASSIGNOR TO AMERICAN MACHINE & FOUNDRY COMPANY, A CORPORATION OF NEW JERSEY

VALVE MECHANISM FOR AUTOMATIC LIQUID WEIGHING SCALES

Application filed December 13, 1929. Serial No. 413,832.

This invention relates to valve mechanism for automatic liquid weighing scales for the purpose of filling containers. The general object of the present invention is to eliminate certain sources of inaccuracy in machines of this type.

When the containers are filled directly from a supply vessel, the pressure at the discharge nozzle is greatest when the vessel is full and least when the vessel is nearly empty; thus, since the rate of flow is greatest when the pressure is greatest, more liquid will pass through the nozzle from the time the valve starts to close due to tilting of the scale up to the time when the valve is fully closed, with the result that the containers first filled are slightly heavier than those last filled.

Also, since inaccuracies due to the flow of liquid after the discharge valve starts to close, and due to drip from the discharge valve, are approximately proportional to the capacity of the valve and the drip surface thereof respectively, a relatively large percentage inaccuracy results when a small container is filled from a large nozzle provided with a large valve. A similar inaccuracy results when a nozzle intended for slow flowing materials is employed in filling with a free flowing liquid. The main object of the present invention is to eliminate such inaccuracies.

With these and other objects not specifically mentioned in view, the invention consists in certain constructions and combinations which will be hereinafter fully described and then more particularly pointed out in the claims hereunto appended.

To the end of effecting the above and other objects, there is provided in the best construction utilized in carrying out the invention, a valve mechanism comprising a main valve of relatively large capacity, and an auxiliary valve of relatively small capacity carried by the main valve for decreasing drip. The best constructions further provide means for maintaining a substantially constant pressure of liquid behind the main valve, whereby the flow of liquid after the valve starts to close will remain the same for each container filled. Preferably, the auxiliary valve is made removable and replaceable by another of differ-

ent capacity. The means above referred to may be widely varied in construction within the scope of the claims, for the particular structure selected to illustrate the invention is but one of many possible concrete embodiments of the same. The invention, therefore, is not to be restricted to the precise details of the structure shown and described.

In the accompanying drawings:

Fig. 1 is a sectional elevation of a device constructed in accordance with the invention; and

Fig. 2 is a detail view in cross-section of the discharge valve shown in Fig. 1.

The drawings, in which like characters of reference indicate the same or like parts, will now be referred to.

To maintain a substantially constant pressure of liquid behind the discharge valve, a tank 10, from which the containers A are filled, is connected with a main supply of the liquid B (not shown) by a pipe 11 which discharges into the tank 10 through an inlet valve 12 controlled by a float 13 in the tank. The float 13 is suspended from a double armed lever 14 by means of a rod 15 attached to a block 16, which rod slides in a guide 17 on the tank 10. The lever 14 is pivoted on a link 18 attached to a fork 19 which is mounted on a valve body 20 and which guides the short arm of lever 14 to which is pivotally connected the stem 21 of the inlet valve 12. On its longer arm, the lever 14 carries a slidable weight 22 by which the level of the liquid B in tank 10 can be accurately adjusted between given limits according to the discharge pressure desired. Fluid from tank 10 passes through pipe 23 into a discharge valve housing 24 whence it flows through the nozzle 25 into container A when the discharge valve is open.

The discharge of liquid from housing 24 to the container A to be filled is controlled by a main discharge valve 26 provided with a stem 27. The stem 27 is guided in the stem 29 of coupling 30 and fastened to the magnet core 31 movable within the solenoid 32, the core 31 descending and thereby closing valve 26 by gravity and by the action of a spring 33 when no electric current flows through the

coil 32. The circuit of coil 32 is controlled by a contact attached to the scale beam of the liquid dispensing scale (not shown) in such a manner that the circuit automatically opens at the moment the scale beam has reached its balance position, thereby causing the valve 26 to shut off the supply of liquid as soon as the container A has been filled to the desired weight, and leaves it closed until an empty container is substituted for the filled one.

In order to decrease drip and other sources of inaccuracy such as those already mentioned, an auxiliary valve 34 is removably secured to the face of the valve 26 by means of a threaded stem 34a screwed into a threaded aperture on the main valve stem 27 so as to seat the valve 34 in the orifice of a discharge nozzle 25. This nozzle is screwed onto the end of housing 24 and thus is readily adjustable for perfect seating and is removable to change the valve seat in said orifice. When the scale is being adjusted for a different size of container or for a different kind of liquid, the nozzle 25 and valve 34 can be easily removed and replaced by a set providing a different size orifice suited for the new conditions.

Thus, in filling small size containers operating with free flowing liquid, by employing the above described construction, a small valve 34 may be used and the amount of flow and drip, after the valve starts to close, correspondingly reduced so that the percentage inaccuracy due to these causes is not substantially greater than when filling large containers.

It will be noted that the two valves 26 and 34, when closed, provide a chamber of very small capacity which serves to catch the drip from the large valve and which also makes for greater accuracy by relieving the auxiliary valve 38 of the pressure of the liquid from the vessel 10, thus avoiding increased drip or slight leakage due to pressure of the liquid. Indeed, there would be little tendency of liquid in the small chamber between the two valves to flow past the valve 34 even though the valve were not quite tight on its seat since such flow would be opposed by the adherence of the liquid to the chamber walls and valve surfaces, and the tendency to form a vacuum in said chamber.

What is claimed is:

1. Valve mechanism for automatic liquid weighing scales comprising a valve stem, a main discharge valve of relatively large capacity immovably mounted on said stem, an auxiliary valve of relatively small capacity carried by the main valve beyond said main valve in the direction of liquid flow to decrease drip, a valve housing having a seat for said main valve, and a nozzle removably secured to said housing and seating said auxiliary valve, said auxiliary valve being removably secured to said valve stem.

2. Valve mechanism for automatic liquid weighing scales comprising a main discharge valve of relatively large capacity, and an auxiliary valve of relatively small capacity carried by the main valve beyond said main valve in the direction of liquid flow to decrease drip, said auxiliary valve being removable and replaceable by another of different capacity.

3. Valve mechanism for automatic liquid weighing scales comprising a valve stem, a main discharge valve of relatively large capacity immovably mounted on said stem, and an auxiliary valve of relatively small capacity carried by the main valve beyond said main valve in the direction of liquid flow to decrease drip, said main valve having a threaded axial aperture and said auxiliary valve having a threaded stem engaging said aperture.

In testimony whereof, I have signed my name to this specification.

WILLIAM E. COOPER.
